(57) **CLAIM**

The ornamental design for a “suspension evaluation tool,” as shown and described.

DESCRIPTION

FIG. 1 is a perspective view of a suspension evaluation tool showing our new design;

FIG. 2 is a front elevational view thereof;

FIG. 3 is a rear elevational view thereof;

FIG. 4 is a lateral elevational view thereof;

FIG. 5 is a top and bottom plan view thereof;

FIG. 6 is a cross-sectional view thereof;

FIG. 7 is a perspective view in an applied status thereof; and,

FIG. 8 is a lateral elevational view in an applied status thereof. The broken lines shown represent unclaimed subject matter and form no part of the claimed design.
